UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed July 29, 1926. Serial No. 125,763.

My invention relates to railway traffic controlling apparatus, and particularly to apparatus of the type wherein governing means on a train is controlled by energy received from the trackway. The present invention relates to the trackway portion of such apparatus, and specifically to trackway apparatus associated with an interlocking plant. One feature of my invention is the provision of means for giving a restrictive indication aboard a train in the section immediately in advance of an interlocking signal if such signal indicates stop, regardless of traffic conditions in advance of such section.

I will describe two forms of trackway apparatus embodying my invention, and will then point out the novel features thereof in claims.

In the accompanying drawing, Fig. 1 is a diagrammatic view showing one form of apparatus embodying my invention and employing loop circuits wherein the train governing current flows in the two rails of a section in multiple. Fig. 2 is a view showing a modification of the apparatus shown in Fig. 1 and also embodying my invention, the apparatus shown in Fig. 2 involving train governing circuits wherein the current flows in opposite directions in the two track rails at a given instant.

Similar reference characters refer to similar parts in each of the views.

Referring first to Fig. 1, the reference characters 1 and 1^a designate the track rails of a railway along which traffic normally moves in the direction indicated by the arrow. These rails are divided by insulated joints 2 to form a plurality of track sections of which only two sections A—D and D—C are shown in the drawing. The section A—D is a section in an interlocking and is protected by an interlocking signal S^b located at the entrance end of this section. The section D—C is protected by an automatic signal S^c, and the section to the left of point A is protected by an automatic signal S^a.

Each track section is provided with a track circuit comprising a source of current at the exit end of the section and a track relay connected across the rails at the entrance end of the section. As here shown, each source of

current is a transformer designated by the reference character T with an exponent corresponding to the location, the secondary of which is connected across the track rails and the primary of which is connected with a source of alternating current which is not shown in the drawing. The track relay for each section is designated by the reference character R with an exponent corresponding to the location.

The automatic signals S^a and S^c may be controlled in any suitable manner, and the circuits for these signals are omitted from the drawing because they form no part of my present invention.

The interlocking signal S^b is controlled by a lever E of an interlocking machine, which lever includes a contact 7 which is open when the lever is in its normal position and is closed when the lever is in its reverse position. The circuit for signal S^b passes from terminal B of a suitable source of current, through contact 7 and the operating mechanism of the signal S^b to terminal O of the same source of current.

Each track section is provided with means for supplying the rails with alternating loop current which flows in the two rails in multiple, and for this purpose a resistance 3 is connected across the rails at the exit end of the section, and a resistance 4 is connected across the rails at the entrance of the section. The immediate source of loop-current supply is a transformer designated by the reference character L with an exponent corresponding to the location, the secondary 15 of which is connected with the two resistances 3 and 4, respectively, of the associated section. Considering section D—C, the primary 14 of transformer L^b is connected with the secondary of a transformer H^b, through a circuit controller 16 operated by the signal S^b and closed only when this signal indicates proceed. The primary of transformer H^b is connected with a suitable source of alternating current which is not shown in the drawing, and the same thing is true of the primary of transformer H^a, hereinafter referred to.

The primary of transformer L^a is supplied with current from the secondary of transformer H^a, the circuit being from the second-

ary of transformer H^A , through contact 5 operated by signal S^A , primary of transformer L^A , and contact 6 on manually operable lever E, to the secondary of transformer 5 H^A . Contact 5 is closed only when signal S^A indicates proceed or caution, and contact 6 is closed only when lever E is in its reversed position, that is, only when signal S^D indicates proceed.

10 The apparatus shown in Fig. 1 is intended for cooperation with train-carried governing mechanism so designed that a restrictive indication is given aboard the train unless the rails of the section occupied by the train are 15 supplied with both track circuit current and loop current.

The operation of the apparatus shown in Fig. 1, is as follows:

When signal S^D is in the proceed position, 20 contact 16 is closed, so that loop current is supplied to the rails of section D—C. Track circuit current is, of course, also supplied to the rails of this section, and, consequently, a train occupying the section will not receive a 25 restrictive indication. If signal S^D is at stop, however, contact 16 will be open, so that the supply of loop current to the rails of section D—C will be discontinued and a train entering this section will receive a 30 restrictive indication. I will now assume that signal S^A indicates either proceed or caution, and that signal S^D indicates proceed. The circuit for the primary of transformer L^A will then be closed at both contacts 5 and 6, 35 so that a train in section A—D will not receive a restrictive indication. If, however, lever E is in the normal position, so that signal S^D indicates stop, the circuit for the primary of transformer L^A will be open at 40 contact 6, and so a train entering section A—D will receive a restrictive indication because the supply of loop current to the rails of this section has been discontinued, and this is true even if the signal S^A indicates proceed or caution, so that contact 5 is closed.

45 It will be seen from the foregoing that the indication given aboard a train in section A—D depends on the position of the interlocking lever E, so that with the apparatus thus far described, it would be possible for the operator to restore this lever to its normal position while a train which has passed signal S^D in the proceed position occupies section A—D. This would cause an unwarranted restrictive indication aboard the train and would, of course, be undesirable. To prevent this, I have provided means for preventing the lever E from being returned to its normal position while a train occupies 50 section A—D. This means in the form here shown, is an electric lock comprising a magnet 9 and a dog 8, which dog is attached to the interlocking lever. The lever E may be moved to the reverse position to clear signal 55 S^D , regardless of the condition of magnet 9,

but owing to the co-action of the armature of magnet 9 with the dog 8, the lever cannot thereafter be restored to its normal position unless magnet 9 is energized. Magnet 9 is provided with a circuit which passes from 70 terminal B of a suitable source of current, through contact 12 operated by signal S^C , contact 11 operated by signal S^D , front contact 10 of track relay R^1 , and winding of magnet 9 to terminal O of the same source 75 of current. This circuit can be closed only when track relay R^D is energized, that is, only when section A—D is unoccupied. The contacts 6 and 7 and the dog 8 are so arranged that when the lever E is in the reverse position it may be moved toward the normal position far enough to open the circuit for signal S^D without interference by the dog 8, but that such movement is not sufficient to open the circuit for the primary of transformer 80 L^A at contact 6. This permits the operator to place signal S^D at stop while the train is in section A—D without interrupting the supply of loop current for that section.

85 Referring now to Fig. 2, the apparatus shown in this view is the same as that shown in Fig. 1 except that the source of track circuit current for each section is a battery 13, and the source of train governing current for each section is a transformer K, the secondary 18 of which is connected across the track rails in series with the track battery 13. The primary 17 of transformer K^D is controlled in the same manner as the primary 14 of transformer L^D in Fig. 1, and the primary 100 17 of transformer K^A is controlled in the same manner as the primary 14 of transformer L^A in Fig. 1.

105 The apparatus shown in Fig. 2 is intended for cooperation with train-carried governing mechanism so designed that a restrictive indication is given aboard a train unless the train occupies a section the rails of which are supplied with train controlling current by the associated transformer K.

110 The operation of the apparatus shown in Fig. 2 will be apparent from the explanation given hereinbefore of the operation of the apparatus shown in Fig. 1.

115 Although I have herein shown and described only two forms of apparatus embodying my invention, it is understood that various changes and modifications may be made therein within the scope of the appended claims without departing from the spirit and 120 scope of my invention.

Having thus described my invention what I claim is:

1. In combination, a section of railway track, an interlocking signal located at the 125 entrance end of said section and controlled at least in part by manual means having normal and reverse positions wherein said signal indicates stop and proceed respectively, means for controlling trains in said section in 130

- accordance with the position of said manual means as well as by traffic conditions in advance of said section, and means for preventing said manual means from being restored to its full normal position while a train is in said section.
2. In combination, a section of railway track, an interlocking signal located at the entrance end of said section and controlled at least in part by manual means having normal and reverse positions wherein said signal indicates stop and proceed respectively, and means for causing a non-restrictive indication to be given on a train occupying said section in spite of operation of said manual means to cause said signal to indicate stop provided said signal gave a proceed indication when it was passed by the train.
3. In combination, a section of railway track, an interlocking signal located at the entrance end of said section and controlled at least in part by manual means having normal and reverse positions wherein said signal indicates stop and proceed respectively, means for causing a non-restrictive indication to be given on a train occupying said section when said manual means is in reverse position and traffic conditions in advance of said section are safe, and means for preventing said manual means from being restored to its full normal position while a train is in said section.
4. In combination, a section of railway track, an interlocking signal located at the entrance end of said section and controlled at least in part by manual means having normal and reverse positions wherein said signal indicates stop and proceed respectively, trackway means for controlling trains in said section in accordance with traffic conditions in advance of the section and in accordance with the position of said manual means, and means for preventing said manual means being restored to its full normal position while said section is occupied by a train.
5. In combination, a section of railway track, an interlocking signal located at the entrance end of said section and controlled at least in part by manual means having normal and reverse positions wherein said signal indicates stop and proceed respectively, means for controlling trains in said section in accordance with the position of said manual means as well as by traffic conditions in advance of said section, a lock for preventing said manual means being restored to its full normal position, and a track circuit for said section including a track relay for controlling said lock.
6. In combination, a section of railway track, an interlocking signal located at the entrance end of said section and controlled at least in part by manual means having normal and reverse positions wherein said signal indicates stop and proceed respectively, and means for supplying train governing energy to the rails of said section under the control of traffic conditions in advance of the section and of said manual means.
7. In combination, a section of railway track, an interlocking signal located at the entrance end of said section and controlled at least in part by manual means having normal and reverse positions wherein said signal indicates stop and proceed respectively, means for supplying train governing energy to the rails of said section under the control of traffic conditions in advance of the section and of said manual means, and means for preventing said manual means from being restored to its full normal position while a train is in said section.
8. In combination, a section of railway track, an interlocking signal located at the entrance end of said section and controlled at least in part by manual means having normal and reverse positions wherein said signal indicates stop and proceed respectively, and means for supplying train governing energy to the rails of said section if and only if said manual means is in substantially its reverse position.
9. In combination, a section of railway track, an interlocking signal located at the entrance end of said section and controlled at least in part by manual means having normal and reverse positions wherein said signal indicates stop and proceed respectively, means for supplying train governing energy to the rails of said section if and only if said manual means is in substantially its reverse position, and means for preventing said manual means from being restored to its full normal position while a train is in said section.
10. In combination, a section of railway track, an interlocking signal located at the entrance end of said section and controlled at least in part by manual means having normal and reverse positions wherein said signal indicates stop and proceed respectively, and means controlled by said manual means for supplying train governing current to the rails of said section in multiple when traffic conditions in advance of the section are safe.
11. In a train governing system of the type wherein the continuous supply of energy from the track rails to a train is necessary to enable the train to proceed without restriction, the combination of a section of railway track, an interlocking signal located at the entrance end of said section and controlled at least in part by manual means, and means controlled by said manual means for supplying train governing energy to the rails of said section when traffic conditions in advance of the section are safe.
12. In combination, a section of railway track, an interlocking signal for said section, a manually operable device having a normal

and a reverse position and an intermediate position, means for preventing movement of said device beyond said intermediate position from its reverse position while said section is occupied, means for causing said signal to indicate proceed when said device is in its reverse position but not when said device is in its intermediate or normal position, and

means subject to control by traffic conditions in advance of said section for supplying train governing current to the rails of said section when said device is in its reverse position or in its intermediate position but not when it is in its normal position. ¹⁰

In testimony whereof I affix my signature.
RONALD A. McCANN.
